(57) **CLAIM**

The ornamental design for a solar light, as shown and described.

DESCRIPTION

FIG. 1 is a top, rear and right side perspective view of the solar light showing my new design;
FIG. 2 is a bottom, front and left side perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front perspective view thereof, with the top section shown in an alternate position; and,

FIG. 10 is a top, rear perspective view thereof, with the top section shown in another alternate position.

The dashed broken lines in the figures illustrate portions of the article that form no part of the claimed design.
